The ornamental design for an ion shield plate base for semiconductor manufacturing apparatus, as shown and described.

(30) **Foreign Application Priority Data**

DESCRIPTION

Jul. 24, 2018 (JP) 2018-016189

FIG. 1 is a front, top and right side perspective view of an ion shield plate base for semiconductor manufacturing apparatus, showing our new design;

(51) **LOC (13) Cl.** **13-03**

FIG. 2 is a rear, bottom and left side perspective view thereof;

(52) **U.S. Cl.**

FIG. 3 is a front elevational view thereof;

USPC **D13/184**; D13/182; D26/138

FIG. 4 is a rear elevational view thereof;

(58) **Field of Classification Search**

FIG. 5 is a right side elevational view thereof;

USPC D13/182, 184, 199; D26/72, 74, 36;

FIG. 6 is a left side elevational view thereof;

D9/435, 445, 454; D15/126, 144.1;

FIG. 7 is a top plan view thereof;

250/496.1, 489, 492.1, 492.2, 492.21,

FIG. 8 is a bottom plan view thereof;

250/506.1, 515.1, 423 R, 424

FIG. 9 is a cross-sectional view taken along line 9-9 of FIG. 7;

CPC H01R 13/46; H01R 31/02; H01J 19/54;

FIG. 10 is an enlarged view of the portion shown in box, labeled, "FIG. 10," in FIG. 9; and,

H01J 1/02; H01J 5/00; H01J 5/02; H01J

FIG. 11 is an enlarged view of the portion shown in box, labeled, "FIG. 11," in FIG. 9.

5/50; H01J 27/00; H01L 33/642; H01L

The broken line boxes shown in FIG. 9 define the enlarged portion views shown in FIGS. 10 and 11 and form no part of the claimed design.

33/644; G21F 5/02; G21F 5/00; G21F

1/00; C25D 5/02; C25D 17/008; C21K
